UNITED STATES PATENT OFFICE.

JULIUS A. SCHWANTES, OF MILWAUKEE, WISCONSIN, ASSIGNOR, BY MESNE ASSIGNMENTS, TO THE PALMOLIVE COMPANY, A CORPORATION OF DELAWARE.

SEALING MACHINE.

Application filed July 25, 1923. Serial No. 653,692.

To all whom it may concern:

Be it known that I, JULIUS A. SCHWANTES, a citizen of the United States, and resident of Milwaukee, in the county of Milwaukee and State of Wisconsin, have invented new and useful Improvements in Sealing Machines, of which the following is a description, reference being had to the accompanying drawings, which are a part of this specification.

This invention relates to improvements in sealing machines, more particularly adapted to applying labels or seals to small packages such as cakes of soap and the like.

It is one of the objects of the present invention to provide a sealing machine which will apply seals to cakes of soap or the like after they have been wrapped.

A further object of the invention is to provide a sealing machine which will moisten the glue on the seals or labels applied to the packages.

A further object of the invention is to provide a sealing machine which will press and secure a label onto each package as it is fed into the machine.

A further object of the invention is to provide a device of the class described which will automatically feed the seals, individually, into package applying position.

A further object of the invention is to provide a device of the class described having means thereon for automatically notifying the operator when the barrels containing the seals have become exhausted.

A further object of the invention is to provide a device of the class described having means to permit the refilling of barrels when one is in feeding position.

A further object of the invention is to provide a sealing machine which is of simple construction, is strong and durable, and is well adapted for the purpose described.

With the above and other objects in view, the invention consists of the improved sealing machine and its parts and combinations as set forth in the claims and all equivalents thereof.

In the accompanying drawing, in which the same reference characters indicate the same parts in all of the views:

Fig. 1 is a front view of the improved sealing machine;

Fig. 2 is an end view thereof;

Fig. 3 is a plan view of the machine;

Fig. 4 is a front detail view on a larger scale, of the mechanism for feeding and securing the seals;

Fig. 5 is a vertical sectional view thereof taken on line 5—5 of Fig. 4;

Fig. 6 is a front detail view on a larger scale, parts being shown in section, of the barrels for holding the seals or labels and the mechanism for automatically feeding the same, individually, into position for application;

Fig. 7 is a plan view thereof;

Fig. 8 is a vertical sectional view taken on line 8—8 of Fig. 7; and

Fig. 9 is an enlarged sectional detail view taken on line 9—9 of Fig. 1.

Referring to the drawings, it will be seen that the numeral 12 indicates the frame of a sealing machine. The power for actuating the movable parts in the machine is transmitted from a source of power (not shown) by means of a chain 13 running over an idler pulley 14 revolute on a shaft 15 to a wheel 16 which is mounted fast on a shaft 17. Adjacent the wheel 16 is a second wheel 18 which is revolved by means of said shaft 17, and by means of a chain drive 19, a wheel 20, mounted fast on shaft 15, is rotated, said last mentioned shaft being also rotated thereby. The inner end portion of said shaft carries a revolute member 21 provided with an arm 22 which is engageable with a Geneva cam 23 mounted on a shaft 24 thereabove. A seal applying member 25 is also mounted on shaft 24 and its hub portion 26 is bolted to said Geneva cam so as to be operated thereby.

Said seal applying member 25 is shaped as shown in Figs. 4 and 5, and is provided with four, spaced, radially extending cylindrical sleeves 27 which are movable between the outer casing 28 of member 25 and inner sleeves 29. Intermittent motion is transmitted to member 25 by said Geneva cam and when member 21 revolves in one direction the Geneva cam and seal applying member 25 will be rotated one-quarter of a revolution to every revolution of member 21. As shown in Figs. 1 and 2, the Geneva movement has just been completed and the seal applying member 25 is idle. In this position, one of the cylindrical sleeves 27 is juxtaposed the opening of a barrel 30 and at this point it is adapted to move into and then out of the mouth of the barrel as shown

in Fig. 4. The mechanism for operating said sleeves will be explained hereinafter. Due to a suction applied at the end 31 of the shaft 24 by means of a pump (not shown) or other convenient means, in connection with a tube or hose 32, there being communicating openings between said sleeves, and the tubular shaft 24, one of the labels or seals 32 contained in the barrel will be sucked against the end portion of the sleeve and will be held thereagainst. The sleeve then moves out of the barrel and the movements of the parts are timed so that at this instance member 25 will again be moved 90°. At this point, the mucilage side of the label held by the sleeve will contact with a roller 33 which is kept wet by means which will hereinafter be explained. Then, member 25 will again be moved 90° so that the sleeve referred to is adjacent the under side of a movable carrier 34 which is mounted above the frame 12 and receives wrapped bars of soap or other packages from a wrapping machine (not shown) and moves the same slowly in the direction indicated by the arrow in Fig. 2. The suction which holds the seal to the cylinder sleeve, as was mentioned, is at this point released, and the seal or label is secured to a cake of soap or package on the carrier. In this connection, it should be noted that the tubular shaft 24 has an oscillating motion. This motion is derived from the shaft 17 by means of a cam 35 carried thereby. Shaft 24 carries a crank 36 from which extends a series of pivotally connected together links 37, 38 and 39. The free end of link 39 has thereon a roller 40 as shown in Fig. 2, and said roller is adapted to ride in the eccentric groove 41 of cam 35. Thus, as said cam revolves, a timed oscillating motion will be transmitted by means of said links and crank 36 to the tubular shaft 24. The end portion 42 of shaft 24 is solid, but is provided with a longitudinally extending aperture 43, and a communicating port 44 which are adapted to register with ports 45. The parts are so arranged and timed that ports 44 and 45 will register when a sleeve is adjacent the carrier. Hence, when the ports register, air will be admitted through the exterior opening 46 of the aperture 43, destroying the suction and blowing the label from the end portion of the sleeve 27. The above described cycle repeats itself and, of course, each of the sleeves 27 is performing the same cycle.

To operate the sleeves 27, a cam 47 is freely mounted on shaft 24 adjacent member 25. A timed, oscillating motion is transmitted to said cam by a grooved cam 48 mounted on shaft 17 and revolved thereby. Said cam 48 has an eccentric groove 49 formed in its face in which a roller 50

rides. Said roller in turn is carried by the end of a link 51 which is pivotally connected with links 52 and 53, the last of which is connected with cam 47, as at 54, to oscillate it. 70

Said sleeves 27 are formed with ratchet portions 55 engageable with cog wheels 56 which are carried within the member 25 on shafts 57 extending transversely through the member 25, as shown. The outer ends of said shafts adjacent the cam 47 are provided with arms 58 and rollers 59 which are adapted to ride on said cam 47. Springs 60 are coiled about the opposite end portions of said shafts between the heads 61 and the surface of member 25, being secured as shown in Fig. 5. Thus, the action of said springs will tend to keep the rollers on the cam 47 at all times. Said cam 47 is so shaped and moved that the shafts 57 which are rotated by the rollers will rotate the cog wheels to raise and lower the sleeves 27 at the desired time. Thus, when a sleeve 27 reaches a barrel 30, the cog wheel 56 will be moved to first slide the sleeve into the barrel and then out of the barrel to normal position. The coiled springs 61' within the inner sleeves 29 assist in returning the sleeves to normal position. 90

As was mentioned heretofore, when member 25 moves so that one of said sleeves is rotated a quarter of a revolution away from a barrel, the mucilage side of a label held by the sleeve will be moistened. To accomplish this, a pan of water 62 is provided having a wheel 63 rotating therein. Said wheel is secured on the end of a shaft 64 which is driven from shaft 17 by means of a chain connection 66 between a gear 65 on said shaft and a double gear 67 on shaft 68. The other portion of the double gear has a chain connection 69 with a gear wheel 70 on said shaft 64. To transfer water from the wheel 63 to a label when a sleeve is in position, the small roller 33, before mentioned, is mounted on a shaft between a pair of bearings 72. The bearings are connected by links 73 and 74 with link 52 and are given a timed back and forth movement thereby to enable the roller to contact with one of the labels. A spring 75 assists in returning the roller to its position against wheel 63. 110

It will be seen that the label holding and feeding mechanism comprises four elongated barrels 30 held by supporting arms 76 mounted on a central shaft 77 which in turn is mounted in a bearing 78 and carries a Geneva cam 79. The bores of the barrels are as shown in Fig. 6 provided with inverted tubular members 80 to form variable false bottoms for the labels or seals 32. The outer portions of the members 80 are notched, as at 81, to engage with dogs 82 pivotally carried by the lower end portions of rods 83. Said rods are slidably mounted 125 130

in bearings 84 and are so positioned that when rollers 59 and arms 58 are forced downwardly by cam 47, one of the rollers will be forced downwardly on one of the heads 85 thereby moving one of the rods 83 longitudinally and the pivot dog 82 carried thereby. One of the coiled springs 86 will then raise the rod to normal position again moving the dog which is in engagement with the notches 81 on the barrel and the member 80 will be raised one notch so that the top label in the barrel may be reached by the sleeve there adjacent. This action takes place on every revolution of the member 25 and in that manner a label is always in position to be fed to the cylinder sleeve. Springs 87, coiled within the confines of members 80, assist in raising said members.

In order that another of the barrels 30 may be swung into position when one has become empty, the bottoms of the portions 88 have elongated shafts 89 hung therefrom, the lower end portions of which are hooked, as at 90. It is evident that the hooked portion will be raised as portion 88 is raised, and said hook rides within a slotted member 91 which is formed integral with a short rod 92 projecting through an aperture 93 in the bottom of the barrel. The rod 92 of the barrel which is feeding the labels is normally engaged by a clutch arm 94. However, when the barrel is feeding the last label, the hook 90 will have reached the top of the member 91. Then, when member 80 is again raised, member 91 will also be lifted by the hook and rod 92 will move above the clutch arm 94. This will permit the clutch arm to be moved to the left by the spring 95 engaging a clutch 96 with a male Geneva cam member 97. Power is transmitted to cam member 97 from shaft 15 by means of a shaft 98 having a bevel gear 99 which is in engagement with a bevel gear 100 on shaft 15. When the clutch is thus in engagement with member 97, the same will be rotated thereby and the arm 101 will engage and move a female Geneva cam member 102 a quarter of a revolution thereby revolving shaft 77. This will bring another barrel 30 into position and its shaft 92 will strike the clutch arm 94 and carry it back to normal position, as shown in Fig. 9, disengaging the clutch. In the manner described, said barrel will stay in position until it has been exhausted of labels and then the next barrel will be moved into feeding position.

In order that the barrels may be removed from the brackets 76 so that they may be filled, spring clips 103, as shown in Fig. 8, are provided. Tongues 104, normally held in slots 105 in said brackets are actuated by said clips against the tension of a spring 106.

When all of the barrels 30 have become exhausted of labels, it is desirable that the operator of the machine be notified. For

this purpose, an open electrical circuit is provided including an incandescent bulb 107, a battery 108, a grounded wire 109 and a lead wire 110 in connection with a switch 111. Obviously, when the barrels are filled, one of the shafts 92 will always engage and hold a switch lever 112, as shown in Fig. 1, thereby keeping the circuit open. However, when the barrels are empty, all of the shafts 92 will be raised so as to clear said switch lever. Hence said lever will pivot to a position to close the switch, closing the circuit and lighting the bulb 107. In this manner the operator of the machine will be notified that the barrels are empty.

From the foregoing description, it will be seen that the improved sealing machine is well adapted for the purposes described.

What I claim as my invention is:

1. A sealing machine, comprising a revoluble member including a plurality of tubular seal containers, a rotary member for transferring the seals individually from said containers to packages, and means for causing the seals to adhere to packages, said rotary member being provided with a plurality of movable members operated by pinion and rack means for removing the seals from the containers and discharging the seals upon said packages.

2. A sealing machine, comprising a member including a plurality of tubular seal containers, a rotary member for transferring seals from the containers to packages, mechanism in connection with said first mentioned member for giving it an intermittent rotary motion, means in connection with said tubular seal containers for automatically allowing the mechanism to revolve said member to bring another container into feeding position immediately after the discharging container has been emptied, a signal means operated when all of the containers have become emptied, and means for causing the seals to adhere to packages which are moved adjacent said rotary member.

3. A sealing machine, comprising a member including a plurality of tubular seal containers, a rotary member for transferring seals from the containers to packages, mechanism in connection with said first mentioned member for giving it an intermittent rotary motion, means in connection with said tubular seal containers for automatically allowing the mechanism to revolve said member to bring another container into feeding position immediately after the discharging container has been emptied, an automatically operated incandescent bulb signal means operated when all of the containers have become emptied, and means for causing the seals to adhere to packages which are moved adjacent said rotary member.

4. A sealing machine, comprising a revoluble member including a plurality of tubular seal containers, a rotary member for transferring seals from the containers to packages, mechanism in connection with said revoluble member for giving it an intermittent motion, a plurality of pinion and rack operated sleeves formed in said rotary member for taking seals from the containers and 10 discharging the seals upon packages, a suction means in connection with said rotary member and sleeves for removing the seals from the containers and holding them adjacent the sleeves, a timed means cooperating with 15 the rotary member for eliminating the suction and depositing the seals upon packages which are moved adjacent said rotary member in successive order, means in connection with said tubular seal containers for automatically allowing the mechanism to revolve 20 said revoluble member to bring another container into feeding position immediately after the discharging container has been emptied, an electric circuit including an incandescent bulb in connection with said tubular containers, said circuit being automatically closed to ignite the bulb when all of the containers are empty, and a cam operated roller for contacting with the seals while 25 engaged by said sleeves to moisten them prior to their disposition upon the packages.

In testimony whereof, I affix my signature.

JULIUS A. SCHWANTES.
